(21) Appl. No.: **29/427,365**

CLAIM

(22) Filed: **Jul. 17, 2012**

The ornamental design for transitioning and nonlinear lacrosse stick handle, as shown and described.

Related U.S. Application Data

(63) Continuation of application No. 12/578,044, filed on Oct. 13, 2009, now abandoned.

DESCRIPTION

(51) **LOC (9) Cl.** 21-02

FIG. 1 is a front perspective view of the transitioning and nonlinear lacrosse stick handle according to an embodiment of our new design.

(52) **U.S. Cl.**

FIG. 2 is a left side view of the transitioning and nonlinear lacrosse stick handle as in FIG. 1.

USPC D21/757

FIG. 3 is a right side view of the transitioning and nonlinear lacrosse stick handle as in FIGS. 1-2.

(58) **Field of Classification Search**

FIG. 4 is a front view of the transitioning and nonlinear lacrosse stick handle as in FIGS. 1-3.

USPC D21/724, 753, 756-757; 473/505-515
See application file for complete search history.

FIG. 5 is a cross sectional view of the transitioning and nonlinear lacrosse stick handle taken on line 5-5' of FIG. 1: and,

(56) **References Cited**

FIG. 6 is a partial cross sectional view of the transitioning and nonlinear lacrosse stick handle taken on line 6-6' of FIG. 5.
